N. C. BRASHEAR

SWIMMING GLOVE

Filed Feb. 26, 1925

FIG. 2.

FIG. 3.

Inventor:—
Norman C. Brashear.
By Martin P. Smith Atty.

UNITED STATES PATENT OFFICE.

NORMAN C. BRASHEAR, OF LOS ANGELES, CALIFORNIA.

SWIMMING GLOVE.

Application filed February 26, 1925. Serial No. 11,676.

To all whom it may concern:

Be it known that I, NORMAN C. BRASHEAR, a citizen of the United States, residing at Los Angeles, in the county of Los Angeles and State of California, have invented certain new and useful Improvements in Swimming Gloves, of which the following is a specification.

My invention relates to a swimming glove, and has for its principal object the provision of a relatively simple, practical and efficient glove that is especially designed to be worn by swimmers and which glove is provided between the fingers and between the thumb and first finger with flexible webs that are adapted while the glove is in use, particularly while the swimmer's hand and arm are drawn rearwardly in stroke, to impinge the water and thereby add materially to speed of the swimmer's movements through the water.

A further object of my invention is, to form and connect the web portions of the glove to the fingers thereof, so that said webs will flex and fold forwardly or toward the palm of the hand when the fingers of the glove are moved toward each other as the hand is drawn forwardly through the water between strokes.

With the foregoing and other objects in view, my invention consists in certain novel features of construction and arrangement of parts that will be hereinafter more fully described and claimed and illustrated in the accompanying drawings in which:

Fig. 1 is a perspective view looking against the rear side of a swimming glove of my improved construction, with the fingers and thumb thereof spread apart and with the webs distended.

Fig. 2 is a cross section taken on the line 2—2 of Fig. 1.

Fig. 3 is an enlarged section of two of the fingers of the glove with dotted lines showing the position assumed by the web when the fingers are brought together.

Referring by numerals to the accompanying drawings which illustrate a practical embodiment of my invention, 10 designates the main body portion of the glove which may be formed of comparatively thin flexible rubber or rubberized fabric, and formed integral with said glove body are finger portions 11 and a thumb portion 12.

Formed on the rear or wrist-engaging

portion of the body 10 is a wristlet 13 that is preferably formed of elastic material that is slightly heavier than the material in the body of the glove and said wristlet is adapted to fit snugly around the wrist of the wearer and prevent water from entering the glove.

Arranged between the fingers and between the thumb and forefinger are webs 14 of thin flexible material, preferably the same material from which the glove and its fingers are formed, and the outer edge of each web terminates in a head or selvedge that serves as a reinforcement and tends to prevent tearing of the outer edge of the webs when the same are in service.

webs 14 are preferably arranged between the central portions of the fingers and thumb and the side portions 16 of said webs are those portions that are disposed immediately adjacent to the finger and thumb portions of the glove and they project inwardly toward the front or palm portion of the glove so as to cause the webs 14 to fold inwardly toward the palm portion of the glove when the fingers are brought together as is the case when the band is partially closed or contracted and drawn forwardly through the water between strokes. (See dotted lines Fig. 3.) This provision and result minimizes resistance offered by the water, as the swimmer's hand is drawn forwardly in the water.

Inasmuch as gloves of my improved construction are of material assistance to swimmers, they may be employed as a safety factor and form a part of the life saving equipment that is generally placed in the passengers' cabins on board ships.

Thus it will be seen that I have provided a swimming glove that is relatively simple in construction, capable of being easily and cheaply produced and is very effective in performing its intended functions.

It will be understood that minor changes in the size, form and construction of the various parts of my improved swimming glove may be made and substituted for those herein shown and described without departing from the spirit of the invention, the scope of which is set forth in the appended claims.

I claim as my invention:

1. A swimming glove formed of thin flexible material, webs of thin flexible ma-

2
terial arranged between the fingers and between the forefinger and thumb of said glove, and those portions of the webs that are connected to and located immediately adjacent to the thumb and finger portions of the glove being tangentially disposed with respect to the walls of said thumb and finger portions so as to cause said webs to tend to fold inwardly when the thumb and fingers of the glove are brought together.

5 2. A swimming glove formed of thin flexible material, webs of thin flexible material arranged between the fingers and be-

10 tween the forefinger and thumb of said glove, those portions of the web that are connected to and located immediately adjacent to the thumb and finger portions of the glove being tangentially disposed with respect to the walls of said thumb and finger portions so as to cause said webs to tend to fold inwardly when the thumb and fingers of the glove are brought together, and the outer edge of each web terminating in a reinforcing selvedge.

15 20 In testimony whereof I affix my signature.
NORMAN C. BRASHEAR.
